UNITED STATES PATENT OFFICE.

FRANK D. SHEPHERD, OF AURORA, ILLINOIS.

POPPET-VALVE MECHANISM FOR INTERNAL-COMBUSTION ENGINES.

1,418,479.

Specification of Letters Patent. Patented June 6, 1922.

Application filed January 30, 1920. Serial No. 355,033.

To all whom it may concern:

Be it known that I, FRANK D. SHEPHERD, a citizen of the United States, residing at Aurora, in the county of Kane and State of Illinois, have invented certain new and useful Improvements in Poppet-Valve Mechanism for Internal-Combustion Engines, of which the following is a specification.

The present invention relates more particularly to valve operating mechanism for internal combustion engines, and may be employed on any type of the same in which valves are utilized for controlling intake and exhaust ports, and the object is to provide mechanism that will be quick-acting in effecting the seating movement of the valve, such seating movement, however, being under mechanical control to avoid the blows that would otherwise be occasioned which would soon destroy the effectiveness of the valve and the seat with which it cooperates.

Several embodiments of the invention are disclosed in the accompanying drawings, but it will be evident to those skilled in the art that other modifications may be employed, and that features as disclosed may be interchanged in various ways.

In the accompanying drawings:—

Figure 1 is a view partly in elevation and partly in section of the well known type of "Liberty" motor, showing the improved apparatus associated with the valve mechanism thereof.

Figure 2 is a vertical sectional view through another type of engine having the valves in the head and illustrating novel mechanism in place thereon.

Figures 3 and 4 are longitudinal sectional views of portions of L or T head engines with different forms of the invention thereon.

Figure 5 is a vertical sectional view of still another embodiment of the invention.

Figure 6 is a vertical sectional view of a well known type of engine with a modified form of valve actuating means.

Figure 7 is a top plan view of the container and mechanism therein shown in Figure 6, with the cap plate and armature removed.

Figure 8 is a detail view of a timer that may be employed for controlling the valve actuating mechanism.

Similar reference numerals designate corresponding parts in all the figures of the drawings.

55 In the embodiment disclosed in Figure 1,

the engine is of the water-cooled type, comprising a cylinder 9 having a head 10 integral therewith, and provided with the usual ports, one of which is illustrated at 11. The ports communicate with a combustion chamber 12, one wall of which is the inner end of a reciprocating piston 13 mounted in the cylinder 9. The ports are surrounded at their inner ends by the usual valve seats, one of which is shown at 14, and cooperating with the seats are the usual movable port controlling valves 15. These valves open inwardly and are provided with outwardly extending stems 16 slidably mounted in the engine head 10. Suitable means are provided for periodically opening the valves, this means in the well known type of "Liberty" motor, consisting of rocker arms 17 that have elements 18 acting on the outer ends of the stems. The rocker arms, as is well known, are carried by rocker shafts 19 intermittently actuated through cam mechanism (not shown).

In the present embodiment, a container 20 surrounds each valve stem and is mounted on the engine head by having an outstanding flange 21 bolted to said head, as illustrated at 22. The container has an inwardly extending sleeve portion 23 fitted in the engine head and containing a replaceable bushing 24 constituting a guide for the stem 16. The outer end of the stem is reduced and threaded as illustrated at 25. Screwed or slipped upon this reduced portion is an outer guide element 26 in the form of a disk having a sliding fit in the container 20. A lock nut 27, threaded on the stem, serves to effectively prevent the disk 26 from becoming dislodged, and in the present embodiment, the bearing element 18 of the rocker arm 17 operates directly against this lock nut. With this construction, it will be noted that the valve stem 16 has not only a sliding bearing in the engine head, but also has a sliding bearing through the medium of the piston disk 26 in the outer end of the container. Consequently the lateral pressure due to the action of the rocker arm on the outer end of the stem is effectively resisted by a sliding bearing of extended area. In order to eliminate any cushioning action or resistance to the inward movement of the disk 26, the container may be provided with relief ports 28 that also allow a free circulation of cooling air or medium.

As thus far described, it will be evident

that the rocker arm 17 serves as a means for opening the valve and will also control the speed of its closing movement. To effect this closing movement the following mechanism 5 is preferably provided.

Mounted in the container 20, between the inner guide bushing 24 and the outer guide element 26 is an electro-magnet 29 that surrounds the stem 16, said stem thus constituting an armature on the magnet. This electro-magnet may be of any well known or desired construction, and the windings thereof may be according to any electrical design. Preferably the magnet is contained 10 within insulating heads 30, and within an insulating cylinder 31 that fits sufficiently within the container 20. This insulation should be of a character to effectively resist the high temperatures the same may be subjected to by reason of its association with an internal combustion engine. The magnet may be held in place by any suitable means, as for instance set screws 32 threaded through container walls having their inner 15 ends projecting over the outer head 30. The terminals of the magnet are shown in the form of binding posts 33, to which are connected leads 34 from any suitable source of electrical current.

With this construction, it will be evident 30 that if the electro-magnet is energized, it will serve to draw the valve stem 16 outwardly and close the valve. The opening movement, however, is effected through 35 the rocker arm 17, and the speed with which the valve can close is determined by the rearward or outward swinging movement of the rocker arm 17 and consequently of cam mechanism which controls the movement of 40 said rocker arm.

In the embodiment illustrated in Figure 2, the cylinder is designated 9^a, and the head 10^a in this embodiment is detachable from the cylinder member and has the usual ports, 45 one of which is shown and designated 11^a. This port is controlled by a valve 15^a having a stem 16^a slidable in a replaceable bushing 24^a. The bushing 24^a is carried by the tubular extension 23^a of the container 20^a, 50 into which the outer portion of the stem 16^a extends. This stem carries at its outer end a guide element in the form of a piston disk 26^a, with a lock nut 27^a for holding the disk in place at all times. The opening 55 movement of the valve is effected by a rocker arm 17^a fulcrumed between its ends, as illustrated at 19^a and actuated by well known mechanism. The closing movement of the valve, as in the previously described embodiment, is effected by an electro-magnet 29^a within the container 20^a, and interposed 60 between the piston disk 26^a and the inner guide 24^a of the valve stem. The valve stem in this embodiment also constitutes an armature for the electro-magnet, and it will be

evident that if desired the stem may have the upper portion thereof indicated at 16^x of non magnetic material, so that the electro-motive force of the magnet may act with greater effectiveness on the lower portion of 70 the stem to move the valve to closed position.

A portion of a well known type of L or T head engine is illustrated in Figure 3, the cylinder being designated 9^b and having an integral head 10^b, with a combustion chamber 12^b with which communicates a port 13^b. The port is controlled by a valve 15^b having a stem 16^b slidably mounted in the extension 23^b of a container 20^b that is located on the 80 under side of the head extension. In this instance the extension 23^b constitutes the sole guide for the stem 16^b, and the opening movement of the valve is effected by a lifter rod 16^y operating against the free end of the 85 stem and actuated in turn by the usual cam shown at 16^z. In the container 20^b is placed an electro-magnet 29^b that operates on the stem 16^b to effect the closing action of the valve, the speed of the closing movement, 90 however, being controlled by the cam 16^z in order to avoid damage to the valve and to the seat.

In Figure 4 the cylinder is designated 9^c, and the head 10^c, said head being in this case 95 removable. The combustion chamber 12^c has communicating therewith a port 13^c controlled by the valve 15^c. The valve has a stem 16^c slidable in a guideway 23^c which in this instance is a part of the engine structure. Fixed to the lower wall of the guideway by retaining bolts 32^c is an electro-magnet 29^c that surrounds the outer portion of the valve stem and acts thereon to effect the closing movement of the valve. The opening 100 movement in the structure disclosed in Figure 4 is effected through a cam 16^l operating on a lifter stem 16^m that in turn acts against the outer or free end of the valve stem 16^c.

Referring now to the embodiment disclosed in Figure 5, the cylinder is designated 9^d and the head is designated 10^d, the same being removable. The combustion chamber 12^d has the usual ports, one of 110 which is shown at 13^d communicating therewith. This port is controlled by an inwardly opening valve 15^d having a stem 16^d slidably mounted in a replaceable bushing 24^d carried by the guide member 23^d that 115 forms a part of the engine structure. The valve is opened by a cam 16ⁿ operating on a lifter rod 16° that transmits motion to the stem 16^d.

The closing action of the valve is effected 125 through the medium of a stem 16^p that is slidably mounted in the engine head 10^d, and has a bearing at its inner end upon the valve head 15^d. The outer end of the stem 16^p is surrounded by a container 20^d mounted 130

on the engine head and having a gas-tight joint therewith. The container encloses an electro-magnet 29^a that operates on the stem 16^a to move the same inwardly, and thus 5 effect the closing action of the valve. In the present form of construction, the electro-magnet 29^a is held in place by a ring 32^a located on said magnet and interposed between the same and a cap plate 28^a detachably secured on the outer end of the container and made gas-tight by a gasket or ground joint. 10

In the embodiment disclosed in Figure 6, the cylinder is designated 9^e, and is provided 15 with a detachable head 10^e. The combustion chamber is designated 12^e and the port communicating therewith is 13^e. Communication between the combustion chamber 12^e and port 13^e is controlled by the movable 20 valve 15^e. The valve 15^e is opened by a stem 16^e slidably mounted in a guideway 23^e and actuated by a lifter rod 16^a that rides against a cam 16^e. The stem 16^e in this embodiment is loose from the valve 15^e and said valve 25 has an integral stem 16^s slidably mounted in the head 10^e and projecting into a container 20^e. This container is provided with a permanent magnet 29^e that operates on a bar or disk armature 26^e carried by the outer end 30 of the stem, and in effect constituting a part of the stem. In the present form of construction the magnet 29^e rests upon an insulator plate 30^e, and is preferably insulated from the walls of the container, as shown 35 at 31^e. The magnet is held in place by an internal shoulder 32^e formed on the walls of the container and overlapping the outer end of the magnet. This type of magnet may be utilized, or as will be evident, its action may 40 be supplemented by coils, as will be obvious.

The means for supplying electric current to the various magnets may be varied to suit the different requirements and conditions met with. Thus a constant current may be 45 employed or a periodic current. In the latter case timing mechanism, as illustrated in Figure 8, may be utilized, the same consisting of a ring of contact elements 35 spaced apart by insulating elements 36 and engaged 50 by a rotary circuit closing member 37. Leads 38 from these contact elements 35 are connected to the various electro-magnets controlling the different valves of the engine. This may be so arranged that when the opening 55 movement of a valve takes place, the magnet that effects the closing movement is deenergized and a reenergization is effected after the opening movement is complete. Thus the resistance to the opening of the 60 valve is materially reduced. It will also be obvious that the magnets may be electrically connected to a magneto or other generator driven by the engine so that the amount of current delivered to the electro-magnets 65 varies with the speed of the engine. This

arrangement has a desirable advantage in that when the engine is operating at a high speed a greater amount of current is delivered to the electro-magnets and the closing movements thus quickened, so that the valve 70 will ride the cam at all speeds and close gas-tight at the right time, thus securing the greatest economy and power. It will be noted that these valves are all free floating and are protected and relieved from any side 75 thrust or wear upon the stems, thus avoiding cocking of the valve in its seat and consequent leakage.

From the foregoing, it is thought that the construction, operation and many advantages of the herein described invention will be apparent to those skilled in the art, without further description, and it will be understood that various changes in the size, shape, proportion and minor details of construction, within the scope of the claims may be resorted to without departing from the spirit or sacrificing any of the advantages of the invention.

Having thus fully described my invention, 90 what I claim as new, and desire to secure by Letters Patent, is:—

1. The combination in an internal combustion engine, of a valve seat and a movable valve coacting therewith, engine operated mechanical means for opening the valve and positively limiting the speed of its closing movement, and electrical means operating on the valve to move it to its closed position. 95

2. The combination in an internal combustion engine, of a valve seat and a movable valve coacting therewith and having a reciprocatory valve stem, mechanical engine-operated actuating means for the valve acting on the free end of the stem to open the 100 valve and positively limit the speed of its closing movement, and electrical means acting on the stem to effect the closing movement of the valve.

3. The combination in an internal combustion engine having a port and a valve movable in opposite directions for controlling the port, of mechanical means operated by the engine to periodically move the valve in one direction to positively open it, means for moving the valve in the opposite direction to close the valve, and mechanism for automatically relieving the valve of the resistance of the closing means during its 110 opening movement.

4. The combination in an internal combustion engine, of a valve seat and a movable valve coacting therewith and having a stem, a guideway in which the inner portion of the stem is slidably mounted, a tubular guide member surrounding the outer portion of the stem and spaced therefrom, a guide disk on the outer end of the stem slidable in the tubular guide member, and a magnet in the tubular member between the inner guideway 125

- and the disk and surrounding the stem, said stem constituting an armature for the magnet.
5. The combination in an internal combustion engine, of a valve seat and a movable valve coacting therewith and having a stem, a guideway in which the inner portion of the stem is slidably mounted, a tubular guide member surrounding the outer portion of the stem and spaced therefrom, a guide disk on the outer end of the stem slidable in the tubular guide member, a magnet in the tubular member between the inner guideway and the disk and surrounding the stem, said 10 stem constituting an armature for the magnet, and means carried by the tubular member and engaging the magnet to hold the latter in place.
6. The combination in an internal combustion engine, of a head, a valve seat and a movable valve coacting with the seat and having a stem slidably mounted in the head, a container on the head surrounding the stem, engine-operated means for periodically 15 operating the valve to open the same and positively limit the speed of its closing movement, and electrical means in the container for effecting the closing action of the valve.
7. The combination in an internal combustion engine, of a head, a valve seat and a movable valve coacting with the seat and having a stem slidably mounted in the head, a container on the head surrounding the stem, engine-operated means at the outer 20 end of the container acting on the stem for periodically opening the valve and limiting the speed of its closing movement, and a magnet in the container surrounding the stem and acting on the same to close the 25 valve.
8. The combination in an internal combustion engine, of a valve seat and a valve coacting with the seat, mechanical means operated by the engine for periodically opening the valve, energizable electrical means for closing the valve, and means for automatically energizing the means between the 30 periods of the opening action and effecting the deenergization thereof during the opening 35 movements.
9. The combination in an internal combustion engine, of a valve seat and a valve coacting with the seat, mechanical means for periodically opening the valve, a generator for magneto electrical current driven by the engine and creating a current proportional to the speed of the engine, and electrical means operated by the current from the generator for effecting the closing movement of the valve. 40
10. The combination in an internal combustion engine, of a valve seat and a movable valve coacting with the seat, a stem for said valve, means for periodically opening the valve and controlling the speed of its closing movement, an electro-magnet mounted on the engine and operating on the stem for effecting the closing movement of the valve, and insulating material enclosing the electro-magnet and comprising material that will resist the heat to which it is subjected by reason of its mounting on the engine. 45
11. The combination in an internal combustion engine, of a valve seat and a movable valve coacting with the seat, a stem for said valve projecting from the engine, means for periodically opening the valve and controlling the speed of its closing movement, a container mounted on the engine and enclosing the stem, an electro-magnet in the container operating on the stem to close the valve, and insulating material interposed between the container and electro-magnet and comprising material that will resist the heat to which it is subjected by reason of its 50 mounting on the engine.
12. The combination in an internal combustion engine, of a valve seat and a movable valve coacting with the seat, a stem for said valve comprising a portion of magnetic material and a portion of non-magnetic material, means for periodically opening the valve and controlling the speed of its closing movement, and a magnet operating on the portion of the valve which is of magnetic material for effecting the closing movement of the valve. 55

In testimony whereof, I affix my signature.

FRANK D. SHEPHERD.
